UNITED STATES PATENT OFFICE.

WILLIAM ADALBERT HARMAN, OF WHITE PASS, DISTRICT OF ALASKA.

FOOT-GUARD.

No. 892,152.

Specification of Letters Patent.

Patented June 30, 1908.

Application filed June 8, 1907. Serial No. 378,040.

To all whom it may concern:

Be it known that I, WILLIAM ADALBERT HARMAN, a citizen of the United States, residing at White Pass, Yukon Territory, 5 Alaska, have invented a new and useful Foot-Guard, of which the following is a specification.

The principal object of the present invention is to provide a guard or stirrup for protecting the shoe while using tamping shovels 10 or the like in railway or other construction work.

In railway construction work where the ballast is tamped by shovels, the shoe of the 15 workmen is rapidly worn out immediately in advance of the heel by contact with the upper edge of the shovel blade, and in carrying out the present invention provision is made for preventing wear of the shoe and injurious 20 pressure on the sole of the foot, by the employment of a metallic guard plate which will engage with the upper edge of the shovel blade and take all the wear.

A further object of the invention is to provide a guard of improved construction which 25 is held from lateral play by contact with the sides of the shoe heel, and further to provide an attaching device which will firmly hold the guard in position and at the same time 30 form a brace for the ankle.

With these and other objects in view, as will more fully hereinafter appear, the invention consists in certain novel features of construction and arrangement of parts, herein- 35 after fully described, illustrated in the accompanying drawings, and particularly pointed out in the appended claim, it being understood that various changes in the form, proportions, size and minor details of the 40 structure may be made without departing from the spirit or sacrificing any of the advantages of the invention.

In the accompanying drawings:—Figure 1 is a perspective view of a foot guard constructed in accordance with the invention. 45 Fig. 2 is a longitudinal sectional view of the same.

Similar numerals of reference are employed to indicate corresponding parts throughout 50 the several figures of the drawings.

The foot guard comprises a plate 10 which may be formed of heavy sheet metal shaped to conform to the in-step and provided with

a downwardly extending flange 11 at its rear edge, this flange fitting against the forward 55 face of the shoe heel. At the opposite ends of the flange are rearwardly bent ears 12 which engage against the sides of the shoe heel in order to prevent lateral displacement of the guard. The opposite edges of the 60 plate are provided with forwardly bent ears 15 to which are pivoted or otherwise secured the ends of straps 16 there being two strap sections secured to each of the ears, one strap section passing from the ear at one side of the 65 plate across the in-step, around the ankle, and the back of the foot, and being buckled to a strap section secured to the same ear. The remaining straps are connected in similar 70 manner, so that the straps will to a certain extent form a brace for the ankle, and will firmly hold the guard from displacement. The lower face of the plate may be provided with teeth or serrations forming a roughened 75 surface to prevent slipping of the guard on the shovel, although this in all cases will not be necessary.

It will be noted that the device is formed of a single sheet of metal which may be shaped by suitable dies, and the edges of the 80 ears which pass up against the sides of the shoes are slightly turned or rounded in order to prevent chafing or cutting of the leather.

I claim:—

An article of manufacture comprising a 85 guard plate for a shoe shank and means for attaching and holding the same in place on a shoe, said means comprising a rearwardly extending integral finger on each side adapted to lie against the heel of the shoe and prevent lateral movement of the guard plate, and a pair 90 of straps fastened on each side of said guard plate the rearmost strap on each side arranged to pass to the back of the shoe and each foremost strap to pass over the instep 95 to the opposite side of the shoe and then backwardly to be fastened to the rearmost strap on the side of its origin.

In testimony that I claim the foregoing as my own, I have hereto affixed my signature 100 in the presence of two witnesses.

WILLIAM ADALBERT HARMAN.
